UNITED STATES PATENT OFFICE.

FRANK A. HOWARD, OF CHICAGO, ILLINOIS.

CARBURETOR.

Application filed July 27, 1918. Serial No. 247,016.

My invention relates to improvements in carburetors and will be fully understood from the following specification taken in connection with the accompanying drawing.

5 In this drawing, Fig. 1 is a diagrammatic central longitudinal section of a carburetor constructed in accordance with my invention; and Fig. 2 is a section on the line 2 of Fig. 1, and showing a top plan view 10 of the throttle-valve.

The carburetor of the present invention is particularly intended for use on internal combustion engines operating under a wide range of speed and load conditions, as, for 15 example, on automobile engines. Among the advantages attainable by the carburetor of the present invention the following may be mentioned:

1. The mixture of volatile fuel and air is 20 initially formed after the expansion of the air beyond the throttle-valve, so that a fuel of lower vapor tension may be employed.

2. The constant level reservoir from which the fuel is withdrawn into the carburetor is 25 exposed to the pressure within the carburetor, or to a pressure which is a function of this pressure, so that an additional element of control for securing proportionality is added.

30 3. The changing vapor pressure of the fuel under different temperatures acts as a thermal correction for the proportions of the mixture.

4. The carburetor is capable of lifting its 35 fuel supply from a tank located at a lower level.

5. The minimum depression within the carburetor is controlled by a throttle-valve of special construction, which operates positively under all ordinary running conditions.

40 6. The fuel admixed with a small proportion of air is heated in an annular chamber surrounding the Venturi tube before admixture with the main stream of air.

45 7. An electrical heater is mounted within the heating chamber in such position as to supply its heat mainly to the fuel itself for starting purposes.

50 8. Many of the foregoing advantages have been attained to a greater or less extent by carburetor constructions heretofore known, but so far as I am aware no successful carburetor has yet been devised in which there 55 was embodied any substantial proportion of these principles and advantages.

Referring to the drawings—

The numeral 10 designates the main air passage of the carburetor, this passage being provided with a manually-controlled 60 throttle-valve 11 at its inlet end, and having a Venturi tube 12 in its outlet section, i. e., that section which is designed for attachment to the intake pipe or manifold of the engine. An annular heating jacket 13 surrounds the outlet end of the carburetor, this jacket being supplied with a heating fluid, such as exhaust gas from the engine. The cylindrical wall of the air passage 10 is continuous from end to end, so that there is 70 formed between the wall of the Venturi tube 12 and the annular jacket 13 an intermediate annular chamber 14, which serves as a heating chamber. A sleeve 15 concentric with the Venturi tube and spaced from the latter 75 as well as from the inner jacket wall serves as a deflector for the fuel and air stream initially formed, and as a support for an electrical heating element in the form of a wire coil 16. Slightly beyond the throat of the 80 Venturi tube 12 the latter is provided with apertures 17, which provide for communication between the interior of the tube and the annular chamber between the tube and the sleeve 15. An aperture 12¹ in the base of 85 the venturi drains the chamber 14.

It will be understood that the showing in Fig. 1 is diagrammatic only and that the parts may be assembled in any desired manner, the particular design of the individual 90 parts so as to permit them readily to assemble and disassemble for inspection and repair not being a part of the present invention.

The throttle-valve 11 consists of two relatively movable sections. The first section, designated 11^a, is pinned or otherwise rigidly secured to the shaft of the throttle-valve, and may have the T-form clearly shown by Fig. 2, the stem of the T serving as a means 100 by which this section of the throttle-valve is affixed to the shaft. The second section of the throttle-valve, designated 11^b, is freely mounted for rotation upon the shaft, its movement in one direction, however, being 105 limited by the wall of the air passage, and in the other direction by the section 11^a, which may have an overhanging tongue 11^c which serves this purpose. The two sections of the throttle-valve are connected by a diametrical tension spring 11^d, which may be made in 110 two sections, as shown, joined by a straight

wire so that the body of the spring may lie as close as possible to the face of the throttle-valve. The air passage 10 beyond the throttle-valve 11 is connected with the annular chamber 14, and through the latter with the venturi 12 by a passage 18 having controlling orifices 19 and 20 at its inlet and outlet ends, respectively. Just beyond the control orifice 19, and in aspirating relationship to the air-jet which issues therefrom, is a main fuel nozzle 21, which may be of the usual form, that is with the nozzle-controlling orifice in the delivery end of the nozzle. This nozzle extends below the normal fuel level 15 in a constant level reservoir 22. The means for maintaining the normal fuel level within this constant level reservoir is diagrammatically illustrated as consisting of a float 23, having affixed thereto a tapered valve 24, which opens and closes the aperture in the fuel delivery pipe 25. In order to illustrate the possibilities of the carburetor, this pipe is shown as connected with a fuel reservoir 26, located below the carburetor and having the fuel therein exposed to atmospheric pressure, as by a vent 27 in the filler cap. The fuel level within the chamber 22 may be regulated by a loading spring 28, which bears upon the top of the float 23 and 30 is adjustable as to tension by a threaded stem 29 extending through the top of the reservoir, and there provided with an adjusting head which is frictionally locked in any adjusted position by a spring 30. The space 35 above the liquid fuel in the chamber 22 is connected with the passage 18 above the fuel nozzle 21 by a tube 31, having one end projecting into the passage 18, this end being preferably turned at an angle, as shown at 40 32. The tube 31 is preferably adjustable about its axis, so as to vary the inclination of the tube-end 32 to the axis of the passage 18. The top of the float chamber 22 may have a very small atmospheric opening 33. 45 Beyond the point at which the float chamber control tube 31 enters the passage 18 there is connected the passage 34, which has its other end open to the atmosphere, the opening being formed in a cap 35 provided 50 with an outwardly-projecting nipple 36. An auxiliary jet nozzle 37 opens into the passage 34 near its inlet end, and in aspirating relationship to the air-jet entering through the nipple of the cap 35. The auxiliary fuel nozzle 37 extends below the normal liquid level in the chamber 22, and has its controlling orifice 38 formed in its inlet end as by drawing down the latter, as illustrated in Fig. 1. 55 The carburetor described in the foregoing operates as follows: The heating coil 16 may be connected with a source of current of proper potential, and thereby brought to a high temperature, the mounting of the coil being such that heat is not transmitted from it readily to the body of the carburetor. This is of importance, since it would in most cases be impractical to provide a heavy enough current flow to heat the body of the carburetor to a substantially increased 65 temperature. If the engine now be cranked, the throttle-valve 11 being at that time closed or partially closed, there will be created within the float chamber 22 by the connection 31 a pressure substantially below atmospheric, and, because the float chamber is below atmospheric pressure while the reservoir 26 is at atmospheric pressure, the fuel will be withdrawn from the reservoir 26 and discharged into the float chamber 22 to fill 70 the latter up to the normal level. Under some conditions, it will be found convenient for the starting of the motor to prime the carburetor, and this may be conveniently done by screwing down the stem 29 until the 75 pressure of the spring 28 exceeds the buoyant effort of the float. Under such conditions fuel will continue to flow into the float chamber until the latter is filled up to the level of the tube 31. In the meanwhile 80 fuel will have been discharged by gravity through the nozzles 21 and 37, and will finally discharge in a relatively large stream through the tube 31. The priming action thus obtained, particularly by reason of the 85 heavy flow of fuel through the relatively large tube 31, will be sufficient to start the motor under the most adverse temperature 90 conditions. It should be here noted as characteristic of the present type of carburetor 95 that the throttling of the air intake passage to create a substantial sub-atmospheric pressure within the carburetor will materially assist in starting the motor. 100 In addition to the factors named, the starting of the motor is further facilitated by the direct impingement of the mixture of air and fuel issuing from the orifice 20 upon the heating coil 16. The latent heat of vaporization is thus supplied to the fuel, and if conditions are such that it is possible for a combustible mixture to exist, it will be formed 105 and will issue from the orifices 17, into the Venturi tube 12, to pass thence to the engine. 110 When the motor is in operation the stem 29 if same has been lowered will be adjusted 115 to permit the float 23 to operate, and to maintain the predetermined constant level within the float chamber. So long as the throttle valve 11 is kept closed, or nearly closed, the velocity through the main air passage 10 is negligible and the pressure difference between the inlet end of the passage 18 and the throat of the venturi is likewise negligible. Under these conditions the main nozzle 21 will not operate, for the reason that there is no substantial difference in pressure 120 between this nozzle and the space above the

liquid level in the float chamber. The auxiliary nozzle 37 will, however, be exposed to the direct aspirating action of the high velocity stream of air entering through the 5 nipple 36, and expanding over the end of the nozzle. The requisite fuel for idle running is thereby supplied to the atmospheric air entering the passage 34, and the mixture thus formed is delivered to the passage 18, 10 thence to the annular chamber 14 to be heated by contact with the wall of the latter, and finally into the Venturi tube.

As the motor is put under load, and the throttle-valve opened, the air in the main 15 passage 10 assumes an appreciable velocity, with a resultant appreciable pressure drop between the throat of the Venturi and the inlet end of the passage 18, whereby there becomes effective upon the nozzle 21 an 20 aspirating depression sufficient to cause the latter to deliver fuel to supplement that delivered by the auxiliary or idling nozzle 37. Further opening of the throttle with resultant increase in the speed of the motor under 25 the same load proportionately increases the delivery of the nozzle 21.

It will be noted that since the passage 34 which is open to the atmosphere at its inlet 30 end enters the passage 18 beyond the nozzle 21, but on the anterior side of the control orifice 20, the velocity of the aspirating air current through the orifice 19 and over the nozzle 21 will be dependent in part upon the absolute pressure within the throat of the 35 venturi instead of being dependent solely upon the difference in pressure between the inlet and throat. The air passage 34 opening at its inlet end to the atmosphere, therefore not only provides the idling mixture 40 through the idling nozzle 37, but cooperates with the delivery from the main nozzle 21 in an inverse manner, i. e., the delivery from the main nozzle tends to decrease relatively 45 to the total mixture passing through the outlet 12 as the inward air flow through the passage 34 increases. It will be understood that the air flow through the passage 34 is increased when the valve 11 is operated to restrict air flow through the passage 18. Since 50 the latter air flow is a function of the absolute pressure or vacuum within the carburetor, and owing to the arrangement of the fuel nozzles a correction factor working in the desired direction for producing a mixture 55 of constant proportions, or even one which is somewhat leaner when a high vacuum exists in the carburetor, is obtained. Thus it will be understood that a high vacuum within the carburetor necessarily indicates 60 a light motor load, and under such load it is necessarily true that economy of fuel rather than maximum power is the result to be aimed at.

The inlet ends of the auxiliary nozzle 37 and auxiliary air passage 34 have been de-

signed with a view to securing a somewhat smaller variation in the delivery of the respective fluids than is attainable by the use of ordinary constructions. The outwardly-projecting nipple 36 on the cap 35 at the end 70 of the air passage acts to impose a loss of head and consequent reduction of delivery of both air and fuel through the passage 34 and this relative reduction of delivery increases very rapidly as the velocity of the 75 entering air increases. This is due to the fact that the vacuum produced while the valve 11 is closed is effective to produce a strong flow through the orifice 36, while almost no flow occurs through 19 because what little air does pass the valve 11 follows the 80 passage 10. As the valve 11 opens, more and more air is drawn through the by-pass 18 with a consequent increase of the amount 85 passing the orifice 19 with no such increase at 36. The delivery of fuel from the nozzle 37 is by the provision of the orifice 38 in the inlet end of the nozzle automatically controlled in a similar manner.

With the throttle 11 nearly closed as in 90 the idling position, very little air passes through the venturi so that there is no tendency to aspirate air through the by-pass 18. What air does pass the throttle valve 11 will pass through the straight tube 10 95 and almost none of it will be drawn through the openings 17 and through the restriction 19 from the lower end of the by-pass 18. This is particularly true since air passing through the opening 36 will, at idling speed, 100 practically supply the demands of the vacuum produced by suction of the venturi through the openings 17. At this speed a large part of the total supply of air will pass through the opening 36.

Under load conditions however with the valve 11 open or partly open, quite the reverse is true. A heavy charge of air passing the venturi will produce a heavy vacuum in front of the openings 17 thereby drawing 110 a heavy charge of air through the by-pass 18 so that a relatively large proportion of the ingoing air will be drawn through the by-pass 18 while at the same time, owing to 115 the fact that the opening 36 is preferably made smaller than the constriction 19, only a relatively small amount of air will pass through the opening 36.

It has hitherto been an objection to all 120 forms of carburetors or motor accessories, where the vacuum of the intake manifold is transferred to the surface of a body of the fuel, such as the so-called vacuum fuel feed tanks, that they would under some conditions seriously disturb the proportions of 125 the mixture by reason of the delivery of fuel vapors into the carburetor, or directly into the intake manifold, as the case might be. For example, an ordinary grade of gasoline used for fuel in motor vehicles has 130

a vapor tension of approximately 300 millimeters at 70° F., this vapor tension increasing very rapidly and becoming practically one atmosphere at 100° F. It is no uncommon thing for the body of a carburetor, or a vacuum fuel feed tank to attain temperatures between 70 and 100° F., or even in excess of this latter figure, and since the depression or vacuum within the carburetor, where the latter is provided with an anterior throttle, or in the intake manifold, exceeds one-half atmosphere where the motor is turning rapidly under a light load and a closed throttle, it will be seen that the fuel may actually boil or fractionate off a considerable proportion of its lighter constituents, and these vapors entering the carburetor or the manifold seriously disturb the proportions of the mixture, particularly since the very condition of maximum vacuum or depression within the manifold which causes this vaporization of the fuel is that condition in which the smallest amount of air is being admitted.

In the carburetor of the present invention this condition of high vapor tension of the liquid fuel, which has hitherto operated to disturb the proportions of the mixture wherever a liquid body of the fuel was exposed to the depression within the manifold, is made to operate as an automatic thermal correction. Thus, it will be seen that whenever the temperature of the fuel within the constant level reservoir 22 is such that its vapor tension is equal to or exceeds the depression within the central portion of the passage 18, fuel vapors will be delivered through the tube 31 to this passage, and as a result of such delivery of vapors the velocity through the orifice 19 and consequently the delivery of liquid fuel from the nozzle 21 will be reduced. Not only does the phenomenon described therefor fail to disturb the proportionality of the mixture, but it may even be advantageously employed as a correction factor offsetting the decrease in viscosity of the liquid, which tends to increase the delivery of the liquid nozzles. This correcting action may be obtained at all temperatures, and with fuels of all measurable vapor tensions by the provision of the atmospheric bleeder opening 33 into the float chamber 22. By providing such an opening there is established a constant flow of air above the liquid level in the float chamber, the tube 31 therefore supplementing the tube 34 as a bleeder device for the passage 18. The quantity of vapor delivered by the tube 31 will be seen to depend upon the vapor tension of the fuel in the reservoir, and the vapors of this fuel will be delivered to the passage 15 to exercise according to their amount the desired temperature controlling function whether the depression within the constant level reservoir is greater than or less than the vapor tension of the fuel.

It has been found that if the Venturi tube 12 is of adequate size to deliver the quantity of mixture required under the maximum load and speed of the engine, it will quite generally need to be so large that the depression at the throat thereof with wide open throttle and minimum motor speed may be insufficient to lift the liquid fuel from the low level tank to the constant level reservoir. To correct this condition, and, furthermore, to limit the minimum vacuum under which the carburetor operates so as to avoid those erratic fuel delivery phenomena which are met with at exceedingly low heads, I provide the special form of throttle valve 11 described. Under all ordinary conditions of operation this throttle valve will respond solely to the manual control, the section 11^a being positively controlled as described, and the section 11^b being constantly held in contact with the stop of the section 11^a by the impact of the air upon its lower face. In the event of the throttle being fully opened, however, while the motor is operating at its lowest speed, the tension of the spring 11^a will be sufficient to hold the throttle section 11^b in contact with the wall of the air passage, and thus partly obstruct the latter, maintaining a minimum difference in pressure between the two sides of the throttle. As the motor speed increases this spring-held section of the throttle will automatically open without imposing any further resistance to the flow of the air, the angularity of action of the spring being such that the automatically moving section of the throttle-valve imposes a resistance of the same character as would a gravity loaded valve.

While I have described in considerable detail a specific embodiment of my invention, together with my theories as to the manner in which the same functions, it is to be understood that this is illustrative only, and for the purpose of making clear the nature and mode of application of the invention, and that I do not regard the invention as limited to the construction described, nor dependent upon the soundness or accuracy of the theories which I have advanced, except in so far as they may be included within the terms of the accompanying claims in which it is my intention to claim all novelty inherent in the invention as broadly as is permissible, in view of the prior art.

What I claim is:

1. In a carburetor, an air passage, a Venturi tube forming a part of the air passage, an annular jacket surrounding the tube and having an inner wall forming with the wall of the venturi an intermediate annular chamber, means for supplying heating fluid to the said jacket, and means for delivering a mixture of fuel and air to the interme-

diate annular chamber to be heated therein, said annular chamber communicating with the venturi. 30

2. In a carburetor, an air passage, a Venturi tube forming a part of the air passage, an annular jacket surrounding the tube and having an inner wall forming with the wall of the tube an intermediate annular chamber, an electrical heating element mounted 10 within the said chamber, means for supplying heating fluid to the said jacket, means for delivering a mixture of fuel and air to the intermediate annular chamber to be heated therein, and openings communicating said 15 chamber and venturi.

3. In a carburetor, a main air passage having a constriction therein, a by-pass delivering into said constriction, an opening in said by-pass communicating with the atmosphere, a fuel delivery nozzle opening into said by-pass, and a throttle anterior to 20 said constriction and by-pass.

4. In a carburetor provided with an anterior throttle, a main air passage having 25 a venturi therein, a by-pass delivering into said venturi near its narrowest part, a main fuel nozzle opening into said by-pass, a constantly open atmospheric inlet opening into said by-pass, and an auxiliary nozzle in

operative relationship to the said atmospheric inlet. 30

5. In a carburetor provided with an anterior throttle, a main air passage having a constriction therein, a by-pass around the constriction and communicating therewith, means for delivering fuel into the said by-pass, an atmospheric opening in the said by-pass, and additional fuel delivery means operable by the atmospheric air entering the by-pass through said atmospheric opening. 35 40

6. In a carburetor provided with an anterior throttle, a main air passage having a constriction therein, a by-pass around the said constriction and communicating therewith, a constriction in the said by-pass, a constant level fuel reservoir, a nozzle opening into the said reservoir and delivering into the by-pass in aspirating relationship to the constriction therein, means for admitting atmospheric air to the said by-pass beyond the 45 50 constriction, an auxiliary fuel nozzle in aspirating relationship to the atmospheric air stream entering the by-pass through said means, and means for applying to the surface of the fuel in the said reservoir the depression existing in the by-pass beyond the second mentioned constriction. 55

FRANK A. HOWARD.
